UNITED STATES PATENT OFFICE.

JOHN WILSON, OF NEW YORK, AND ALLAN MASON, OF BROOKLYN, ASSIGNORS TO HERBERT H. SANDERSON, TRUSTEE, OF NEW YORK, N. Y.

APPARATUS FOR MAINTAINING COMBUSTION IN SECONDARY CHAMBERS OF BOILER OR OTHER FURNACES.

SPECIFICATION forming part of Letters Patent No. 438,873, dated October 21, 1890.

Application filed March 8, 1888. Serial No. 266,566. (No model.)

To all whom it may concern:

Be it known that we, JOHN WILSON, of New York city, and ALLAN MASON, of Brooklyn, Kings county, New York, citizens of the United States, have invented certain new and useful Improvements in Apparatus for Maintaining Combustion in Secondary Chambers of Boiler and other Furnaces; and we do declare the following to be a full, clear, and exact description of the invention, such as will enable others skilled in the art to which it appertains to make and use the same, reference being had to the accompanying drawings, and to the letters of reference marked thereon, which form a part of this specification.

Our invention relates to boiler and other furnaces in which one or more secondary combustion-chambers are employed with the objects of securing more effectual combustion of the gaseous portions of the fuel and more effective application of the heat than is obtained with a single combustion-chamber, and is especially designed for the greater and more economical generation of steam in marine and other boilers through the instrumentality of a secondary combustion-chamber at the rear or opposite end from the primary furnace-chamber and communicating with it to receive and consume the unconsumed gases and return the heat products through the upper portion of the boiler; but our invention is also designed, generally, for all similar or other furnaces in which secondary combustion may be advantageously utilized; and it consists of the combination, in a boiler or other furnace, of the primary combustion-chamber and the secondary combustion-chamber, respectively, located at the extremities of a material part of the heating portion of the furnace, injector apparatus furnishing a continuous supply of fuel elements, as oil, steam, and air, into said primary chamber, separate injector apparatus of fuel elements, as oil or comminuted coal, to the secondary chamber, and burner apparatus in said secondary chamber separately supplied with and burning other like fuel independently of the fuel supplied to the primary chamber, as hereinafter fully described, reference being made to the accompanying drawings, in which—

Figure 1 is a longitudinal sectional elevation of a boiler-furnace, showing the application of an auxiliary hydrocarbon fire in the secondary combustion-chamber for effectual combustion of the gases entering said chamber from the front or primary chamber, in which we have in this instance represented apparatus for the use of hydrocarbon fuel and steam. Fig. 2 is a horizontal section of a similar furnace in which the auxiliary fire of the secondary chamber is supported in part by hydrocarbon fuel and in part by coal-slack, both introduced with air, the fire in the front furnace being of coal or other fuel, as preferred. Fig. 3 is a longitudinal sectional elevation of a similar furnace in which the auxiliary fire in the secondary chamber is maintained with coal-slack blown in and burned on a coal fire, which, being an ordinary fire made on a coal-grate to begin with, is subsequently maintained and continued by the supply of coal-slack, the fire in the front furnace being produced in this instance with hydrocarbon fuel injected with steam and air. Fig. 4 is a top view of a burner for oil on an enlarged scale.

We are aware that it has been attempted to consume in secondary chambers such gases as fail of complete combustion in the first chamber, it being supposed that sufficient room being provided the heat of the primary chamber would be sufficient for effecting such combustion; but we find such method is a failure, practically, although it may work at times and under some circumstances; but generally the gases are too much chilled to insure continuous combustion, and when extinguished by fall of temperature or other causes fail to relight even when considerable increase of temperature takes place. Hence we find an auxiliary fire in the secondary chamber an imperative necessity for practical efficiency; but such a fire as is commonly made by intermittent supplies of fuel through the ordinary fire-door will not do, because when the door is opened it stops the draft in both fires, besides admitting cold air in great excess, and therefore materially interferes with both fires, and if a fan-blower is used to urge the main fire, as is commonly the case with marine boilers, the door cannot be opened

without first stopping the fan, and the fan also interferes with magazine feeders and other automatic stokers for the auxiliary fire by forcing more or less gas out through them.

5 To overcome these difficulties and to secure a reliable and uniform auxiliary fire adapted to insure effectual combustion of the unconsumed gases from the main fire, having a continuous forced supply of fuel elements, 10 as oil, steam, and air, we have contrived a system which comprises the continuous and unobstructed forced supply of the elements of combustion in various forms to the continually-closed secondary chamber in addition to the gases entering it from the main furnace, the arrangement being such that the same is controllable at the front, where the main fire is tended, and so that the apparatus is applicable to and detachable from ordinary 15 furnaces constructed with a secondary chamber without change or permanent attachment.

The apparatus which we prefer to use is variable to some extent at the option of the constructor and for different forms of the combustibles to be used; but what we claim 20 is substantially as follows, the process being claimed in a prior application filed December 5, 1887, Serial No. 256,997.

In the boiler-furnace represented in the 25 drawings, *a* indicates the main or primary combustion-chamber, and *b* the secondary chamber, each having the customary fire-door *c* and ash-pit door *d*, with the usual system of fire-tubes *e* communicating between them, also 30 the return system of tubes *f*, connecting the secondary chamber with the smoke-flue *g*.

In Figs. 1 and 3 we represent an injecting apparatus for the use of oil, steam, and air for combustion in the main furnace, *h* being 35 a steam-nozzle, *i* an air-inlet funnel, and *j* an oil-feeding tube, one or more of the latter being used to deliver oil on the upper surface of the steam-nozzle to conduct the oil off the end of the nozzle suitably to mix and atomize or va-

porize with the steam and air, the steam-nozzle 40 to be suitably connected with the boiler and the oil pipe or pipes to be connected with any source of supply, with suitable regulating-cocks or other devices, and all being suitably connected with the furnace through the fire-door of the first combustion-chamber. With 45 this method of producing combustion in the main chamber *a* we provide for an auxiliary fire in the secondary chamber *b* by a series of oil-burners *n*, supplied with oil and air 50 through the ash-pit and one or more of the fire-tubes *e* by the pipes *o* and *l*, and any approved means of injecting them, with which 55 we may also burn coal-slack, to be forced in through a pipe or pipes *m* by a fan *p* or other means; or we may use the coal-slack 60 with an ordinary coal fire *q* to begin with, and to be subsequently maintained by the coal-slack alone.

What we claim, and desire to secure by Letters Patent, is—

The combination, in a boiler or other furnace, of the primary combustion-chamber and the secondary combustion-chamber respectively located at the extremities of a material 70 part of the heating portion of the furnace, injector apparatus furnishing a continuous supply of fuel elements, as oil, steam, and air, into said primary chamber, separate injector apparatus of fuel elements, as oil or comminuted coal, to the secondary chamber, and burner apparatus in said secondary chamber, separately supplied with and burning other like fuel independently of the fuel supplied to the primary chamber, substantially as described.

In testimony whereof we affix our signatures in presence of two witnesses.

JOHN WILSON.
ALLAN MASON.
